his ATTORNEY:

UNITED STATES PATENT OFFICE.

MAURICE COUADE, OF PARIS, FRANCE, ASSIGNOR TO PATHÉ CINEMA, ANCIENS ETABLISSEMENTS PATHÉ FRERES, OF PARIS, FRANCE.

MEANS FOR OBVIATING THE ACTION OF HEAT IN A PROJECTOR UPON THE BACKING OF THE IMAGES TO BE PROJECTED.

Application filed November 8, 1925, Serial No. 66,468, and in France November 15, 1924.

In known practice, the heating action of the projecting beam upon the backing or support of the images to be projected, is obviated by delivering currents of air upon one or both sides of said backing, but in this event only a part of the air which is thus supplied can be utilized for the cooling of said backing, since the air expands in the atmosphere when discharged from the supply conduits.

In certain devices, a stream of air is circulated between said backing and a glass plate disposed on the side next the condenser, and herein the air under pressure will blow the backing into a curved shape if it is flexible as in cinematographic films, this effect depending upon the force of the stream.

It has further been proposed to place between the condenser and said backing a glass plate consisting of a material absorbing the heat rays, but such plates only absorb a portion of the heat and cut off a great part of the light.

The present invention has for its object a device whereby we obviate the action of the heat from a beam of light from a projector upon the backing of the images to be projected, by means of a surface cooling of said backing by a current of air. Said device consists essentially in the fact that it comprises a narrow sheath in the middle part of which is disposed the backing of the image—film or plate—the front and rear walls of said sheath consisting of a transparent substance such as glass, mica, or the like; the sheath is traversed by a current of air which passes upon the two faces of said backing. Since the pressure and the air circulation are the same on both sides of the backing, the latter will remain in a flat position and will also be cooled. The said device permits of eliminating the use of heat absorbing glass, and in this manner the entire output of the illuminant is maintained.

The transparent walls may consist either of glass plates with parallel faces or of plano-convex lens elements whose convergent effect will be combined at the rear part with that of the condenser and in front with that of the objective.

The appended drawing shows by way of example two embodiments of said invention.

Fig. 1 is a section of a first embodiment

perpendicular to the direction of the film. 55 Fig. 2 is a similar section of a second embodiment.

In Fig. 1, 1 is the backing for the image or images to be projected; 2 is the frame of the device; 3 and 4 are two transparent 60 walls disposed on either side of the backing 1. The air which is supplied under pressure through the conduit 5 will pass over both faces of the backing 1 and will then escape into the atmosphere in the direction of the 65 arrow f.

The devices shown in Fig. 2 is a modification of Fig. 1, and like reference numerals indicate corresponding parts. The modification consists in the form of the transparent walls which herein consist of plano-convex lenses 6 and 7 with the plane part 70 facing the interior of the sheath.

Obviously, the invention is not limited to the construction shown in the drawing, and in particular the current of air, instead of being supplied transversally with reference to the backing, may be supplied in a vertical or oblique direction, provided the pressure is the same on both sides of the 80 backing.

Having now described my invention, what I claim as new and desire to secure by Letters Patent is:

1. In a projection apparatus the combination of a front and a rear transparent wall respectively disposed on either side of the support for the images to be projected and whereby a narrow sheath for said support is provided, with means for causing a 85 current of air to flow throughout said sheath and over both faces of said support always in the same direction from one edge to the other edge of said support.

2. In a projection apparatus the combination of a front and a rear transparent wall respectively disposed on either side of the support for the images to be projected and whereby a narrow sheath for said support is provided, an air inlet conduit opening 95 laterally into said sheath in front of the edge of said support and means for circulating air through said conduit and sheath, always in the same direction from one edge to the other edge of said support.

3. In a projection apparatus the combination of front and rear glass plates with parallel faces respectively disposed on either

side of the support for the images to be projected and whereby a narrow sheath for said support is provided with means for causing a current of air to flow throughout said sheath and over both faces of said support always in the same direction from one edge to the other edge of said support.

4. In projection apparatus the combination of front and rear plano-convex lens elements respectively disposed on either side

of the support for the images to be projected and whereby a narrow sheath for said support is provided with means for causing a current of air to flow throughout said sheath and over both faces of said support always in the same direction from one edge to the other edge of said support. ¹⁵

In testimony whereof I have signed my name to this specification.

MAURICE COUADE.
